(57) **CLAIM**

The ornamental design for a covered hair clip, as shown and described.

DESCRIPTION

FIG. 1 is a front view of my covered hair clip;
FIG. 2 is the opposite side front view of my covered hair clip thereof;

FIG. 3 is a perspective view thereof;

FIG. 4 is a side view thereof; the opposite side is a mirror image thereof; the broken lines are for environmental purposes only and form no part of the claimed design

FIG. 5 is a top view thereof;

FIG. 6 is a bottom view thereof;

FIG. 7 is a front view of my covered hair clip with more teeth;

FIG. 8 is the opposite side front view of my covered hair clip with more teeth thereof;

FIG. 9 is a perspective view with more teeth thereof;

FIG. 10 is a side view with more teeth thereof; the opposite side is a mirror image thereof; the broken lines are for environmental purposes only and form no part of the claimed design

FIG. 11 is a top view with more teeth thereof;

FIG. 12 is a bottom view with more teeth thereof;

FIG. 13 is a front view of my covered hair clip with fewer teeth;

FIG. 14 is the opposite side front view of my covered hair clip with fewer teeth thereof;

FIG. 15 is a perspective view with fewer teeth thereof;

FIG. 16 is a side view with fewer teeth thereof; the opposite side is a mirror image thereof; the broken lines are for environmental purposes only and form no part of the claimed design

FIG. 17 is a top view with fewer teeth thereof; and,

FIG. 18 is a bottom view with fewer teeth thereof.
